UNITED STATES PATENT OFFICE.

JESSE M. BARNETT, OF WILKINSBURG, PENNSYLVANIA.

APPARATUS FOR MANUFACTURING CONCRETE BLOCKS AND THE LIKE.

Application filed September 10, 1924. Serial No. 736,833.

Generally speaking my invention comprises improvements in movable cores by means of which the internal cavities of the concrete blocks or other units are formed.

5 Such cores are extended into the mold cavity or cavities before the concrete is poured, and then, after the concrete has set, the cores are retracted before the blocks are removed from the mold.

10 In the case of multiple molds wherein a plurality of blocks are simultaneously produced, the cores are preferably extended into the mold cavities and retracted therefrom in unison, and in my present invention I provide new and improved means for 15 extending and retracting the cores.

Again, I provide novel means for insuring the proper engagement of the cores with the floor or wall of the mold cavity 20 through which they extend into position for the pouring operation, thus insuring the proper positioning of the individual cores and preventing leakage or waste of the fluid concrete.

25 I show a multiple mold wherein the cores are extended upwardly through the floor of the mold cavities, and in the accompanying drawings for the sake of clearness of disclosure I have illustrated the principles of 30 my present invention applied to such a multiple mold.

In the present practice where a plurality of cores are extended and retracted in unison, or by means of some operative mechanism, the failure of one or more of the cores to properly respond to the actuations of the operative mechanism prevents the proper extension and seating of the remaining cores. Thus the presence of particles of 35 concrete, pebbles or the like may prevent one of the cores from assuming its proper position, and the remaining cores likewise fail to properly seat, thus frequently resulting in the malformation of the concrete 40 blocks or in the escape by leakage of a portion of the liquid concrete.

45 Therefore I provide novel means whereby the failure of one or more of the cores to properly seat or assume its extended position is prevented from affecting the operation of the remaining cores.

In the preferred form of this feature of my invention the connection between the cores and their operative mechanism is of 50 a resilient character.

I also provide novel means whereby the

cores in their extension movement are properly guided into position, thereby preventing such angular displacement of the cores which might result in their sticking or binding. 60

Other novel features of construction and also of arrangement of parts will appear from the following description.

In the accompanying drawings, wherein 65 as already explained, the principles of my invention are illustrated as applied to a multiple mold, Fig. 1 is a broken longitudinal and vertical section of a multiple mold to whose cores my invention is shown applied; 70 Fig. 2 is an enlarged vertical section of one of the cores; Fig. 3 is a detail on enlarged section taken at right angles to that of Fig. 2 and showing the wrist-pin connection between the core and its pitman; Fig. 4 is a 75 further enlarged detail of the same, and Fig. 5 is a diagrammatic view showing the method of limiting the angularity of a core relative to its operative means.

The following is a detailed description of 80 the drawings.

A represents the multiple mold platform which is provided with a floor B. 1 represents one of the end walls of the multiple mold, 2 one of the transverse partitions, and 85 3 one of the longitudinal partitions.

I do not show or describe the construction of the multiple mold in detail, as the same does not form in itself a part of the present 90 invention.

However, it will be understood that by means of the end walls and the longitudinal and transverse partitions a multiplicity of mold cavities are formed, the partitions being of the take-down type so as to be assembled for pouring and removed after the 95 concrete blocks are set.

The floor B is provided with a plurality of apertures 4 which are preferably arranged in longitudinal rows and are individually positioned so as to occur at the proper places in the bottom of the several mold cavities when the partitions are assembled as shown in Fig. 1. C represents the movable cores, one for each aperture 4 100 and which are preferably cast or otherwise formed of suitable metal, such as aluminum.

The cores are made hollow to save weight and cost of metal, and also to facilitate their attachment to their operative mechanism. 105

Said cores are preferably of rectangular cross section as the internal cavities of the

concrete blocks are usually rectangular. However, the cores may be of any cross sectional shape, depending on the shape of the cavities to be formed in the blocks.

5 The cores are preferably tapered or contracted towards their upper end or their ends first inserted through the apertures. Thus their proper centering in the mold cavities and also their withdrawal from the 10 said concrete in the blocks are facilitated.

The walls of the core apertures 4 are of proper taper to fit the taper of the cores, and the apertures are of proper size to fit snugly around the bases of the cores. The 15 bases of the cores are preferably provided with a perimetral lip 5 which fits against the underside of the floor B. I prefer to place a compressible gasket 6 on the lip 5, which when compressed between the lip and the floor forms a water tight joint and thus 20 prevents leakage from the mold cavity.

In the embodiment shown the cores are extended upwardly and retracted downwardly in unison.

25 I have shown the cores extended and retracted by means of crank shafts. I regard this as the most satisfactory method of operating the cores, but it will be understood that any suitable operative mechanism may 30 be provided for that purpose.

It is evident that if the cores are positively connected to the crank shafts or other operative mechanism, their extension and retraction will not only be simultaneous, but 35 to the same degree. Thus in case particles of concrete, pebbles or the like happen to obstruct the extension of one of the cores the extension of the remaining cores will likewise be prevented or breakage will result. 40 I therefore provide a new and improved connection between the operative mechanism and the individual cores, so that the obstruction of one of the cores which prevents its proper seating or extension will not affect 45 the proper seating or extension of the remaining cores.

In the embodiment shown such means have a resilient characteristic whereby the 50 resistance of a core to properly seat in its extended position is taken up by resilient compression between said core and its operative mechanism. This resilient characteristic also provides for the elastic compression 55 of the gasket, and thus aids in insuring a water tight joint.

Thus in the drawings I have shown the connecting rods 7 pivotally mounted on the cranks 8 of the crank shaft D, whose ends are shown extending through a bearing hole 9 in the end member 10 of the platform A. The shaft is properly journaled in bearings 11 carried by the cross beams 12 of the platform. The other ends of the connecting rods 7 are inserted into sockets 13 in the ends of the pitmen E and are held rigidly in place

therein as by set screws 14. The other ends of the pitmen E are provided with transversely disposed cylindrical heads 15 having axially disposed trunnions 16 on their ends. The trunnions 16 are journaled and 70 slideable in the opposed slotted bearings 17 in the legs of the yoke member F. The yoke member F is provided with a threaded stem 18 which is screwed into the threaded hole 19 in the center of the head of the core 75 C. G represents a bearing plate slidably mounted on the stem 18, and 20 represents a helical spring coiled about the stem between the head of the core C and the plate G, thus 80 resiliently separating the same.

21 represents pins slidably mounted in longitudinal bearing holes 22 of the yoke F, and which have their inner ends seated and 85 preferably fixed as by welding in the sockets 23 in the face of the plate G. The other ends of said pins are provided with arcuate feet 24 which ride on the trunnions 16.

It is thus evident that as the crank shaft moves the cores into their extended position, the moving force is transmitted to a core, through the connecting rod 7, the pitmen E, the trunnions 16, the pins 21, the plate G and the spring 20 to the core. Thus when the core seats the gasket 6 is resiliently compressed between the lip 5 and the floor B, 95 thus insuring a water tight joint between the core and the floor of the mold cavity. In case a pebble, as shown at 25 in Fig. 1, or other obstruction, is lodged between the lip and the floor so as to prevent the core properly seating in the aperture, such obstruction or premature stoppage of one of the cores, as for instance the right hand core in 100 Fig. 1, does not interfere with the proper extension and seating of the other cores, since the premature halting of the obstructed core 105 simply results in the greater compression of the spring 20 of that particular core and does not interfere with the seating of the remaining cores. When the cores are retracted 110 the trunnions 16 engage the lower ends of the slotted bearings 17, and thus retract the cores.

It is evident that by the use of my invention, only the improper extension or seating 115 of the core which happens to be obstructed would result, so that any leakage of concrete or malformation of the block would be confined to that particular core.

When the cores are being extended, owing 120 to the angularity assumed by the pitmen the cores are liable to be tipped out of the vertical, and may in some cases bind or stick in the apertures before they are completely 125 extended or seated unless some means to control the tipping tendency of the cores is provided.

I provide against the assumption of excess angularity on the part of the cores by 130 providing set screws 26 which are screwed

laterally into the pitmen near their inner ends and whose projecting heads contact with the interior walls of the core to limit the tipping of the latter. As a suitable abutment against which the heads of said set screws may strike, I have shown ribs 27 formed in the interior of the core. Projections or abutments of any kind may of course be provided for this purpose, or the set screws be of greater length so as to directly engage the interior walls of the core. The set screws may be adjusted to limit the tipping of the core to any desired degree.

The method which I show for connecting the cores to the operative mechanism, such as the crank shaft shown, is novel and highly advantageous. The point of connection is at the head of the core, so that when the core is retracted or withdrawn from the set concrete the pull is applied at the upper end of the core and thus the core is disengaged more easily than if the attachment was at the lower end of the core or intermediate of its length.

It will be noted that, while the seating of the cores in their extended positions is resiliently effected through the springs 20, the retraction of the cores is positive, thus insuring their uniform withdrawal.

What I desire to claim is:—

1. In a mold for casting concrete blocks and the like, the combination with the wall of the mold cavity provided with a suitable aperture, of a movable core, operative mechanism for extending said core through the aperture into the cavity and for retracting the same therefrom, and means for taking up the force of said operative means when the core abnormally resists assuming its extended position.

2. In a mold for casting concrete blocks and the like, the combination with the wall of the mold cavity provided with a suitable aperture, of a movable core, operative mechanism for extending said core through the aperture into the cavity and for retracting the same therefrom, and a resilient lost-motion connection between the operative means and the core for the purpose descriptive.

3. In a mold for casting concrete blocks and the like, the combination with the wall of the mold cavity provided with a suitable aperture, of a movable core, operative mechanism for extending said core through the aperture into the cavity and for retracting the same therefrom, and connection between said operative mechanism and said core, said connection including resilient means for assuming the force of said operative means in case the core abnormally resists proper extension.

4. In a mold for casting concrete blocks and the like, the combination with the wall of the mold cavity provided with a suitable

aperture, of a movable core adapted to be extended through the aperture into the mold cavity and to be retracted downwardly therefrom to strip the core from the formed block, said core having a portion which when the core is extended engages said wall to form a joint at said aperture, operative mechanism for extending and retracting said core, and means for exerting spring compression on said joint, when the core is extended, to prevent leakage.

5. In a mold for casting concrete blocks and the like, the combination with the wall of the mold cavity provided with a suitable aperture, of a movable core adapted to be extended through the aperture into the mold cavity and to be retracted therefrom, said core having a portion which when the core is extended engages said wall to form a joint at said aperture, a compressible gasket interposed in said joint, operative means for extending and retracting said core, and means for exerting spring compression on said joint, when the core is extended, to prevent leakage.

6. In a mold for casting concrete blocks and the like, the combination with the wall of the mold cavity provided with a suitable aperture, of a movable core adapted to be extended through the aperture into the mold cavity and to be retracted therefrom, a crank shaft, and connecting rod mechanism coupling the core to said crank shaft, said mechanism including spring means for resiliently seating the core in its extended position.

7. In a mold for casting concrete blocks and the like, the combination with the wall of the mold cavity provided with a suitable aperture, of a movable core adapted to be extended through the aperture into the mold cavity and to be retracted therefrom, a crank shaft, connecting rod mechanism coupling the core to the crank shaft, and spring means interposed in said connection whereby the force of the crank shaft is taken up when the core abnormally resists seating in its extended position.

8. In a mold for casting concrete blocks and the like, the combination with the wall of the mold cavity provided with a suitable aperture, of a movable core adapted to be extended through the aperture into the cavity and to be withdrawn therefrom, a crank shaft, connecting rod mechanism coupling the core to the crank shaft, and means for limiting the angularity of the core to prevent its binding in the aperture during its extension movement.

9. In a mold for casting concrete blocks and the like, the combination with the wall of the mold cavity provided with a suitable aperture, of a movable core adapted to be extended through said aperture into the cavity and to be retracted therefrom, said

- core being hollow with a closed head, a crank shaft, and connecting rod mechanism coupling the core to the crank shaft, said connecting rod mechanism being connected to the head of the core.
10. In a mold for casting concrete blocks and the like, the combination with the wall of the mold cavity provided with a suitable aperture, of a movable core adapted to be extended through said aperture into the cavity and to be retracted therefrom, said core being hollow with a closed head, a crank shaft, and connecting rod mechanism coupling the core to the crank shaft, said connecting rod mechanism extending into the interior of the core and being connected to the head thereof.
11. In a mold for casting concrete blocks and the like, the combination with the wall of the mold provided with a plurality of suitable apertures, of a movable core for each aperture and adapted to be extended through the aperture into the mold and to be retracted therefrom, common operative means for all of said cores, and individual connections between each core and said operative means, such connections including resilient means for assuming the force of said operative means in case a core abnormally resists proper extension.
12. In a mold for casting concrete blocks and the like, the combination with the wall of the mold provided with a plurality of suitable apertures, of a movable core for each aperture and adapted to be extended through the aperture into the mold or to be retracted therefrom, common operative means for all of said cores, means for coupling said cores to said operative means, and means whereby the cores are individually seated in their extended position, regardless of the proper seating of the remaining cores.
13. In a mold for casting concrete blocks and the like, the combination with the wall of the mold provided with a plurality of suitable apertures, of a movable core for each aperture and adapted to be extended through the aperture into the mold or to be retracted therefrom, common operative means for all of said cores, and individual connections between each of said cores and said operative means, said connections including resilient means for assuming the force of said operative means in case a core abnormally resists proper seating in its extended position, thereby preventing interference with the proper seating of the other cores.
14. In a mold for casting concrete blocks and the like, the combination with the wall of the mold provided with a plurality of suitable apertures, of a movable core for each aperture and adapted to be extended through the aperture into the mold and to be retracted therefrom, a crank shaft, and a connecting rod mechanism coupling each of said cores to the crank shaft, said connecting rod mechanism including means for assuming the power of the crank shaft when a core abnormally resists seating in its extended position.
15. In a mold for casting concrete blocks and the like, the combination with the wall of the mold provided with suitable apertures, of a movable core for each aperture and adapted to be extended through the aperture into the mold and to be retracted therefrom, a crank shaft, a connecting rod mechanism coupling each of said cores to the crankshaft, and resilient connection between each connecting rod mechanism and its associated core, whereby when a core abnormally resists seating in its proper extended position the power of the crank shaft will be assumed without affecting the seating of the other cores.
16. In a mold for casting concrete blocks and the like, the combination with the wall of the mold provided with suitable apertures, of a movable core for each aperture and adapted to be extended through the aperture into the mold and to be retracted therefrom, a crankshaft, a connecting rod mechanism coupling each of said cores to the crank shaft, and spring means cushioning the application of extension movement by the individual connecting rod mechanism to the corresponding cores.
17. In a mold for casting concrete blocks and the like, the combination with the wall of the mold provided with suitable apertures, of a movable core for each aperture and adapted to be extended through the aperture into the mold and to be retracted therefrom, a crank shaft, a connecting rod mechanism coupling each of said cores to the crank shaft, and means interposed between the individual connecting rod mechanisms and the corresponding core whereby the extension movement of the connecting rod is resiliently transmitted to the core.
18. In a mold for casting concrete blocks and the like, the combination with the wall of the mold provided with suitable apertures, of a movable core for each aperture and adapted to be extended through the aperture into the mold and to be retracted therefrom, a crank shaft, a connecting rod mechanism coupling each of said cores to the crankshaft, and means interposed between the individual connecting rod mechanism and the corresponding core whereby the extension movement of the connecting rod is resiliently transmitted to the core, and the retraction movement is positively transmitted to the core.
19. In a mold for casting concrete blocks and the like, the combination with the wall of the mold provided with suitable ap-

tures, of a movable core for each aperture and adapted to be extended through the aperture into the mold and to be retracted therefrom, a crank shaft, a connecting rod mechanism coupling each of said cores to the crank shaft, resilient connection between each connecting rod mechanism and its associated core, whereby when a core abnor-

mally resists seating in its proper extended position the power of the crank shaft will be assumed without affecting the seating of the other cores.

Signed at Pittsburgh, Pa., this 5th day of September, 1924.

JESSE M. BARNETT.
